UNITED STATES PATENT OFFICE.

FRANK CRAWFORD, SR., OF NEW BRUNSWICK, NEW JERSEY, ASSIGNOR TO THE CRAWFORD MANUFACTURING COMPANY, OF NEW BRUNSWICK, NEW JERSEY, A CORPORATION OF NEW JERSEY.

STOP MOTION FOR KNITTING MACHINES.

Application filed December 6, 1923. Serial No. 678,966.

The main object of my invention is to provide means for holding the trip mechanism positively, while the operator is adjusting the several stop motion devices and is

5 placing the thread in position, said means holding the trip mechanism until released by the knitting machine when it is set in motion.

A further object of the invention is to 10 construct the stop motion so that it will stop the mechanism of the knitting machine automatically when a thread is broken, or when a thread becomes entangled.

A still further object of the invention is 15 to connect the upper and lower mechanisms so that the upper mechanism will actuate the lower mechanism to stop the machine when a thread becomes entangled.

Still another object of the invention is to 20 provide means for setting the two mechanisms in proper alignment when the parts are shipped to a mill for assemblage.

In the accompanying drawings: Fig. 1 is a 25 vertical elevation illustrating my improved stop motion mounted on a circular knitting machine, part of the machine being shown in dotted lines;

Fig. 2 is a plan view of the lower stop motion;

30 Fig. 3 is a side view of the lower stop motion;

Fig. 3^a is a sectional view on an enlarged scale of a portion of the mechanism shown in Fig. 3;

35 Fig. 4 is a plan view of a portion of the lower stop motion with the cap plate removed and showing the mechanism before tripping and the ring held in position;

Fig. 5 is a detached view showing the ring 40 released;

Fig. 6 is a sectional view on the line 6—6, Fig. 4;

Fig. 7 is an enlarged sectional view similar to Fig. 4; showing the mechanism 45 tripped;

Fig. 7^a is a sectional plan view of the locking mechanism of the lower stop motion, the parts being in the same position as in Fig. 7;

Fig. 7^b is a diagrammatic view showing 50 certain parts in the locked position;

Fig. 8 is a sectional view on the line 8—8, Fig. 4;

Fig. 9 is a perspective view, showing the

coupling and the arm for actuating the trip mechanism in the lower stop motion by 55 means of the mechanism in the upper stop motion.

Figs. 10 and 11 are detached views of the means for setting the upper and lower stop motion in the proper relation to each other; 60

Fig. 12 is a plan view of the upper stop motion with the cap removed and the arms broken away;

Fig. 13 is a sectional view on the line 13, 13, Fig. 12;

Fig. 14 is a detached perspective view of 65 a portion of the disk of the upper stop motion;

Fig. 15 is a view in outline showing the means for actuating the release mechanism 70 by means of the basket carrier or other movable part of a knitting machine where the bobbins remain stationary; and

Figs. 16 to 24 inclusive are detached perspective views of parts of the trip mecha- 75 nism.

Referring to the drawings, the head 1 of the knitting machine is mounted in the usual manner. The spider 2 is supported by posts 3; this spider carries the upper mechanism 80 of the machine.

There are two stop motions 4 and 5. The upper stop motion 5 is supported by a post 6 which extends through the lower stop motion. The lower stop motion mechanism is 85 enclosed within a casing 7 which is provided with a cap plate 8.

A ring 9 is located within the casing 7. The ring is supported at intervals on arms 10 so as to turn freely in the casing. Se- 90 cured to the casing are hollow brackets 11, through which pass rods 12. Each rod has at its inner end an arm 13, which extends into a slot 14 in the ring 9 and turns the ring when a thread breaks or becomes en- 95 tangled. On the outer end of each of the rods 12 is an arm 13^a located in a casing 20 on the end of each bracket. Adjustably mounted on an extension 11^b of the bracket 11 is a hub 15 having a bar 15^a on which are adjustably mounted the guide eyes 16—16 and at the centre of the hub is a guide eye 16^a. On the hub is a circular stop plate 15^b. The hub is frictionally held by a nut and spring washer, so that it will remain in 100 position after adjustment.

Fig. 7^b is a diagrammatic view showing certain parts in the locked position; Fig. 8 is a sectional view on the line 8—8, Fig. 4; Fig. 9 is a perspective view, showing the

A short shaft 18 has its bearing in the casing 20. On one end of this shaft is an arm 17 carrying a ring 19 which is held close to the stop plate 15^b when a thread 5 is in the eyes, but is free to drop when a thread breaks. On the opposite end of the short shaft 18 is an arm 18^a which engages the arm 13^a of the shaft 12 when a thread breaks. This shaft imparts movement to 10 the ring 9, which, in turn, releases the trip mechanism.

The hub 15 can be turned so as to bring the guide eyes into alignment with a guide ring and the needles.

15 On the ring 9 is an arm 21 which has a finger 21^a projecting in front of the trip lever 22. This lever has a short extension 22^a which is arranged to engage an arm 23^a of a latch 23 (Fig. 19). The latch has a hooked 20 arm 23^b which engages a hooked arm 24 of the trip mechanism 25.

The hooked arm 24 is pivoted at 24^a and is slotted at 24^b. Working in the slot 24^b is a pin 70^b carried by an arm 70, which is 25 pivoted at 71. In the arm 70 is a slot 70^a into which extends a pin 72 on a cam disk 73. The cam disk 73 actuates a two armed hold back lever 74, on one arm of which is a flange 75 which engages a hold back catch 30 76 which has a projection 77.

The hold back catch is pivoted at 78 and engages the rib 82 on the underside of the ring 9 when the machine is stopped and is being threaded.

35 When the arm 74^a of the hold back lever is in the notch 73^a of the cam disk the arm 74^b of the lever retains the hold back catch in the engaging position.

A push back lever 79 is pivoted at 80. 40 This lever has a roller 81 that is held against the cam disk 73. A lever 35 pivoted at 35^a has an extension 36 that engages the projection 77 on the hold back catch 76. This catch engages a rib 82 on the ring 9 and holds the ring in the locked position to enable the operator to thread the machine without releasing the stop motion. The lever 35 has a slotted extension 83. An arm 33 on a head 30 extends into the slot. The 45 head 30 is mounted on a shaft 28. On turning the shaft, the arm 33 moves the lever 35 so as to withdraw the hold back catch 76 clear of the rib 82. This allows the ring to have free movement. The arm 28 has, at its outer end, an arm 84, which is in the path of a wiper 85 on a rod 86 that is adjustably mounted on a standard 87, clamped to the main frame of the knitting machine. The head 30 has a flat portion 31 against which bears a plunger 32. Back of this plunger is a spring 32^a. The head is slotted at 88. Extending into the slot is a stop 8^a, which forms part of the top plate 8. This stop 8^a limits the movement of the shaft 28.

65 The ring 9 is held out of action by the

catch 76 until the head of the knitting machine begins to make its first revolution. When the arm 84 on the shaft 28 comes in contact with the wiper 85 the shaft is turned and imparts movement to the lever 35, which withdraws the hold back catch 76 from engagement with the ring 9. The stop motion is now in position to stop the machine should a thread break or a thread become entangled.

70 The trip mechanism 25 turns a shaft 26, which extends from the lower casing 7 and is connected to the ordinary mechanism (not shown) for shifting the belt and stopping the rotation of the knitting machine.

75 Mounted in a bearing 37 on the cap 8, above the trip mechanism, is a shaft 38, that has an arm 39, (Fig. 9) which is moved to trip the lever 22. This shaft is coupled to a rod 40. The coupling 41 is of the universal type. The shaft 38 has arms 42 which enter slots in the head 43 that is secured to the rod 40. The upper end of the rod is coupled to a shaft 44 by a universal coupling 45 similar to the coupling 41. The shaft 44 is mounted in a bearing 46 in the casing 5 of the upper stop motion and has a slotted arm 47 at its upper end within the casing.

80 A disk 48 is located in the casing 5 of the upper stop motion. This disk is mounted on a stem 49 pivotally mounted in an extension 50 of the casing. Depending from the disk is a rod 51, which extends into the slot in the arm 47 so that, when the disk is turned by the mechanism of the upper stop motion, this movement trips the mechanism 25 of the lower stop mechanism through the rod 40 and the shaft 38. The pivot 49 of the disk is mounted on a set screw 52 and is held in place by an arm 53. A coiled spring 54 surrounds the pivot and is attached at one 105 end to the disk and at the other end to the projection 50 so that the spring returns the disk to its normal position, after being actuated by one of the arms of the stop motion.

110 Projecting radially from the casing 5 are arms 55 under which are located rods 56. The rods have, at their outer ends, spring controlled trip arms 57, over which the threads pass. Carried by the arms 55 are guards 58, which normally engage the outer 115 ends of the trip arms 57 and function to prevent the accidental displacement of the thread, but allow the thread to be released when it becomes tangled or caught by the point of the arm 57 moving out of contact with the respective guard 58. The rods 56 have, at their inner ends, arms 59, which enter slots 60 in the depending flange 61 of the disk 48. Two of the arms 56 are connected by springs 62 to arms 63 on an adjustable member 64. An adjusting screw 65 passes through a nut on the adjusting member. On returning the screw, more or less tension can be applied to the two arms. The other two arms are connected to an upper 130

adjusting member 66 by springs 67. This adjusting member is adjusted by means of a screw 68, which passes through a nut on the adjusting member so that, on turning the screw, the tension on the two rods may be regulated. In Fig. 1, a machine is illustrated in which the stop motion rotates and the needle cylinder is stationary.

In Fig. 15 is shown a means for operating the hold back catch when the mechanism is applied to a machine in which the stop motion is stationary and the needle cylinder rotates.

A shaft 28 withdraws the latch 76 through the lever 35. A standard 87^a is clamped to the frame of the knitting machine, and extending through this standard is a shaft 90 having at its upper end a slotted arm 91 which engages an arm 92 on a shaft 86^a 20 on which is a wiper 85^a arranged to engage the arm 84^a and turn the shaft 28^a. On the lower end of the shaft 90 is a short arm 91^a carrying a lever 92 which is in the path of the rotating basket frame 93 of the knitting machine. Between this lever 92 and the arm 91^a is a spring 94 which cushions the blow when the frame strikes the lever.

In order to set the lower and upper stop mechanisms in proper alignment when the parts are shipped to a mill for assemblage, a sleeve 95 (Figs. 10 and 11) is provided which is slotted to engage a pin 96 on the shaft 38 when raised as in Fig. 11, being held in place by a pin 97 on the bearing engaging a bayonet slot 98 in the sleeve 95. When the sleeve is in this position the shaft is in proper position in respect to the tripping mechanism. When the machine is set up the sleeve is lowered as in Fig. 10, freeing the shaft 40 from the control of the sleeve.

The operation is as follows: When a thread breaks or becomes entangled, the stop motion automatically stops the knitting machine. In order to re-thread the machine, the ring controlling the stop mechanism is held out of action so that the operator is free to thread the machine without the liability of the mechanism being released by too much tension being placed on a thread, or allowing the thread to become slack, either of which would set off the mechanism under working conditions.

After the thread guides of the upper and lower stop motions are threaded, the knitting machine is set in motion. During the first revolution of the machine, the holding mechanism is actuated by the knitting machine, which releases the ring and allows it to function in the event of a thread being broken, caught, or entangled. When a thread breaks, then the lower mechanism is actuated directly. When a thread becomes entangled, or caught, so that undue tension is applied to the thread, the upper mechanism is actuated. 65 This movement of the upper mechanism is

applied to the lower mechanism through the rod, stopping the machine.

When a thread breaks the ring 19 held by the broken thread falls, turning the shaft 18. This shaft turns the shaft 12 through arms 18^a 70 and 13^a (Fig. 3^a). The arm 13 moves the ring 9 and the arm 21 on the ring moves the trip lever 22 which engages an arm 23^a of the latch 23, withdrawing the latch from engagement with the hooked arm 24. The arm 24 moves the arm 70 on its pivot, releasing the pin 72 of the cam 71. The cam is mounted on the shaft 26 which is turned as soon as released by a spring (not shown), and which forms part of the shifting mechanism.

When the stop motion is set the roller 81 of the hold back lever 79 is resting against a step 73^b of the cam disk 73 and holds the cam against accidental movement until the 85 pin 72 is released from the control of the arm 70.

If a thread becomes entangled then the mechanism of the upper stop motion is actuated, the arm 59 on the shaft 56 is turned 90 by the tension of the thread. This arm turns the disk 48 and its rod 51 turns the shafts 44, 40 and 38. The arm 39 on the shaft 38 actuates the trip lever 22 of the lower stop motion, releasing the mechanism in the manner previously described. 95

The arrangement of the levers and arms makes the stop motion very sensitive. During the knitting operation the mechanism is held out of action positively, but the instant 160 a thread breaks or undue tension is placed on a thread the mechanism is released immediately and the machine is stopped.

I claim:

1. The combination in a stop motion for 105 knitting machines, of means for holding the stop motion out of action while the machine is being threaded; and means actuated by the movement of the knitting machine when first set in motion to release the stop mechanism and allow it to function. 110

2. The combination in a stop motion for knitting machines, of upper and lower stop mechanism; means in one of said mechanisms for stopping the knitting machine; 115 means for locking the stop motion out of action to allow the operator to thread the machine; and means on the machine for releasing the holding means when the knitting machine is first set in motion. 120

3. The combination in a stop motion for knitting machines, of a rotatable ring adapted to normally move freely and at certain times to be held in a predetermined set position; trip mechanism actuated by the ring to stop the machine; stop mechanism for actuating the ring; means for retaining the ring in the set position to allow the operator to thread the machine; and means actuated by the knitting machine as it starts to re- 125 130

lease the retaining means and to allow the ring freedom of movement.

4. The combination in a stop motion for knitting machines of a casing; a movable ring mounted in the casing; a series of stop mechanisms having arms arranged to engage the ring and to move it when a thread breaks or becomes entangled; a rib on the ring; a hold back catch engaging the rib of the ring to hold the mechanism out of action while the operator is threading the machine; a shaft having a pin; a hold back lever engaged by the pin; and means on the knitting machine for turning the shaft when the machine is first set in motion so as to actuate the hold back lever and withdraw the hold back catch from engagement with the rib on the ring.

5. The combination of a casing; stop mechanism; a ring actuated by the stop mechanism; release mechanism operated by the ring; an arm on the ring; a latch controlling said release mechanism; a pivoted arm at the release mechanism engaged by the arm on the ring when the ring is moved; and a catch engaging said release latch and actuated by the arm, said catch when actuated releasing the mechanism that stops the machine.

6. The combination in a stop motion for knitting machines, of a lower stop motion having a rotatable ring; trip mechanism released by the movement of the ring and actuating the mechanism for stopping the knitting machine; a series of arms on the lower stop motion having thread guides and trip mechanism held in place by the threads so that, when a thread breaks, the ring is turned and the mechanism is tripped; an upper stop motion having a trip mechanism; actuated when a thread is under excessive tension, a rod extending from the lower stop mechanism; a shaft to which the rod is connected; and an arm on the shaft for actuating the trip mechanism from the upper stop motion.

7. The combination in a stop motion for

knitting machines, of a casing; a ring mounted in the casing; stop mechanism for actuating the ring when a thread breaks; trip mechanism released by the ring; a means for resetting the trip mechanism and the ring and a shaft having a head at its outer end; a pin on the head; a lever engaged by the pin, a plunger for holding the shaft in its normal running position; and means for actuating the shaft when the machine begins to rotate after the stop motion has been set.

8. The combination in a stop motion of trip mechanism therefor, a pivoted thread guide composed of a rod having end eyes and a central eye; an arm attached to the trip mechanism and having a ring encircling the central eye, said ring being held in place by the thread passing through the eyes.

9. The combination in a stop motion, a bracket, a head pivoted to the bracket, friction means for holding the head; a disk on the head; a rod on the head having an eye at each end; an arm for releasing the stop motion; a ring on the arm arranged to be held in position by the thread passing through the eyes for maintaining the said arm in a normal inoperative position and adapted to move said arm to an operative position to effect the operation of the stop motion when said ring is released by the thread.

10. The combination in a stop motion for knitting machines, of upper and lower stop mechanism; means at the lower mechanism for stopping the movement of the machine; a rod extending from the upper stop motion; a shaft having a lever and connected to said rod; a locking sleeve arranged to be raised and lowered, said sleeve, when raised, engaging the shaft and preventing it turning so that, when the mechanism is set up, the operating mechanism of the upper stop motion will be locked properly in relation to the mechanism of the lower stop motion.

FRANK CRAWFORD, Sr.
